[57] CLAIM

The ornamental design for a cap, as shown and described.

DESCRIPTION

FIG. 1 is a top, front and right side perspective view of a cap showing our new design

FIG. 2 is a front elevational view thereof;

FIG. 3 is a top plan view thereof;

FIG. 4 is a right side elevation thereof

FIG. 5 is a rear elevational view thereof; and,

FIG. 6 is a left side elevation thereof.

The bottle shown in phantom is for context only and forms no part of the new cap design.
